STAMP CONTAINING ADVERTISING DEVICE

Charles E. Petherbridge and Charles F. Buckland, Long Island City, N. Y.

Application April 8, 1932. Serial No. 603,954

5 Claims. (Cl. 206—46)

The invention relates to containers for postage stamps. It is well known that many retail dealers sell postage stamps to their customers as a matter of accommodation, in that they derive no profit from such sales except the incidental good will which may result from the accommodation. It must also be obvious to most people that the conditions under which such stamps are kept and dispensed are highly unsanitary. Not only are the stamps, which many people moisten on their tongues, kept in open boxes which are often dirty and dusty, but the stamps are handled by many unclean hands before the purchaser receives them.

15. The main object of the present invention is to remedy these conditions, first by assuring the dealer some remuneration, in the form of increased sales from advertising, for his expense and labor in selling the stamps, and secondly by assuring the purchaser that the stamps are kept and dispensed in a sanitary manner.

Another object is to provide a moisture-proof container for stamps so constructed that the number of stamps it contains may be ascertained 25 without opening it. A further object is to provide ample space for advertising purposes on the container, and a still further object is to provide a device of simple and sanitary construction, from which the stamps may be easily removed, 30 and which can be manufactured at a very low price.

These and other objects and advantages will be readily understood from the following description and from the accompanying drawing of preferred embodiments of the invention in which, however, certain modifications may be made without departing from the scope of the appended claims. In the drawing

Fig. 1 is a perspective view of the container, 40 Fig. 2 is a plan view showing the container open,

Fig. 3 an end view,

Fig. 4 a plan view of the container slightly modified, and

45. Fig. 5 end view of Fig. 4.

Referring first to Figs. 1, 2 and 3, the device comprises a cover consisting of a front and a rear leaf 10 and 11 which are folded on the line 12. This cover is preferably made of cardboard or stiff paper. A piece of transparent oiled or waxed paper is folded so as to form a flat tube 13 in which a plurality of stamps 14 are inserted. This tube is formed with a flap 15 which is folded and glued, or otherwise secured, to one of the 55 leaves adjacent to the fold 12.

The tube is transversely perforated, as at 16. The perforations align with the perforations of the stamps contained in the tube. To assure correct alignment, the perforations in the tube are preferably made oblong, as shown, instead of circular as on the stamps. A plurality of holes 17, corresponding to the number of stamps contained in the tube, are punched in the front cover 10. Through these holes the stamps may be seen in the transparent tube. It is evident that both 65 sides of the leaves 10 and 11 may be imprinted with advertisements.

In Figs. 4 and 5, the stamp container 13, instead of being tubular, is channel-shaped so that an open space 18 is left on top of the container. 70 In this case, the member is not perforated.

The device is employed in the following manner: the stamps are mechanically inserted in the tube 13, thus eliminating the danger of contamination from the hands of the operator. The device is sold to the retailers and here again the stamps are not exposed to dirt or contamination. The purchaser receives the stamps in a sanitary condition and may remove one or more at a time; either by tearing off a part of the tube 13 with 75 the stamp, as in Fig. 1, or by sliding out one or more stamps as in Fig. 4, and separating it or them from the remaining stamps. In either case the remaining stamps are untouched by the hands of the user. By looking through the hole 17 in 80 the front cover the number of stamps remaining in the device may be readily ascertained.

While we have shown only one stamp tube in each cover, it will be understood that a plurality of such tubes may be used, either superposed one 85 upon another or placed side by side.

From the foregoing it will be seen that this device is a simple, sanitary and inexpensive one for dispensing stamps, and that it is admirably adapted for advertising purposes.

Having described our invention and its advantages, what we claim as new and wish to protect by Letters Patent is:

1. In a device of the class described; a cover; a separate container hinged at one end within 100 said cover and constructed of non-adhesive, moisture-proof material having its opposite edges folded to form a slide for holding a strip of stamps; and means for removing said stamps, one at a time from said container.

2. In a device of the class described; a cover; a separate container hinged at one end within 105 said cover and constructed of non-adhesive, transparent, moisture-proof material having its opposite edges folded to form a slide for hold-

- ing a strip of stamps; means for removing said stamps, one at a time, from the said container; and means provided in the cover for ascertaining the number of stamps in the container.
5. 3. In a device of the class described; a cover; a plurality of separate containers hinged at one end within said cover and constructed of non-adhesive, moisture-proof material having its opposite edges folded to form a slide for holding 10 a strip of stamps; and means for removing said stamps, one at a time, from said container. 80
4. In a device of the class described; a cover; a plurality of separate containers hinged at one end within said cover and constructed of non- 85
- 15 adhesive, transparent, moisture-proof material having its opposite edges folded to form a slide for holding a strip of stamps; means for remov- 90
